UNITED STATES PATENT OFFICE.

THEODORE S. COLE, OF NEW HAVEN, CONNECTICUT, ASSIGNOR TO THE SAFETY CAR HEATING & LIGHTING COMPANY, A CORPORATION OF NEW JERSEY.

BATTERY-PLATE CONSTRUCTION.

Application filed October 8, 1924. Serial No. 742,353.

This invention relates to storage battery construction and more particularly to plate construction for such storage or secondary batteries.

5 One of the objects of this invention is to provide a storage battery plate of simple and practical construction and efficient action. Another object is to provide a plate construction which will be capable of relatively inexpensive and rapid manufacture and simple and rapid assembly for actual practical use. Another object is to provide a construction of the above nature, as well as a storage cell which will be strong and durable, and capable of long and dependable service. Another object is to provide such a construction wherein the material of the plate is sufficiently utilized to afford not only a large proportion of active surface, but 25 also mechanical strength to meet dependably the conditions of hard practical use. Another object is to provide such a construction wherein provision is made for effectively taking care of expansion of the metal of the plate either during formation of the plate or in operation, more particularly expansion in different degrees, without detracting from other thoroughly practical advantages of the invention. Other objects will be in part 30 obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing, in which is shown one of the various possible embodiments of this invention.

40 Figure 1 is a vertical, substantially central, sectional view of a storage cell, showing in side elevation a plate unit, certain parts being broken away to show the construction more clearly.

45 Figure 2 is a sectional view as seen along the line 2-2 of Fig. 1, certain parts being omitted, and

50 Figure 3 is a fragmentary sectional view on a larger scale as seen substantially along the line 3-3 of Fig. 2, certain parts being omitted.

55 Similar reference characters refer to similar parts throughout the several views of the drawing.

Referring now to the drawing and more particularly to Figure 1, there is indicated generally at 10 a container, in general of rectangular shape, and composed of any suitable inert material, such as, for example, 60 hard rubber or a suitable alloy, as lead-antimony, which materials are substantially unaffected by the electrolyte, such as sulphuric acid. The bottom member 11 of the container 10 is provided with a plurality of 65 upstanding ribs 12, extending transversely of the container 10, and in Figure 1 being shown as two in number. These members 12 are preferably made integral with the bottom member 11 in order that the former 70 may mechanically reinforce the latter. Within the container 10 and supported upon the upstanding ribs 12 is a plurality of active plates, one of which is generally indicated in Figure 1 at 13, and is shown in this 75 figure in side elevation. Inasmuch as these plates, the number of which may vary in accordance with the capacity which it is intended that the storage cell shall have and the positive and negative members of which 80 are arranged alternately, are preferably of similar construction, it will suffice to consider in detail the construction of only one of these plates.

85 Each plate, as the plate generally indicated at 13, is built up of a plurality of sheet-like sections or leaves positioned face to face, electrically connected together, as will be more clearly hereinafter described, and mechanically held together in assembled relation. In Figure 2 of the drawing, in which is clearly shown a section of one of these plates, the latter is shown as being formed of four sheet-like sections or leaves, generally indicated at 14, 15, 16 and 17. These sheet-like sections 14, 15, 16 and 17 are preferably 90 formed of sheet lead, and in so far as the specific details of construction of these individual sheets is concerned, I prefer to embody therein the construction disclosed 100 in my co-pending application, Serial No. 400,996, filed August 3, 1920 patented Jan. 13, 1925. Patent No. 1,522,613. Accordingly, reference may be had to my above-mentioned disclosure for these preferred 105 features of construction, but it may be noted here that each sheet-like section 14, 15, 16 and 17, of lead, is preferably formed out of sheet lead having a thickness in the neighborhood of one-twentieth of an inch; each 110

of these sheet-like sections is shaped, by any suitable mechanical means, into the form substantially shown in the drawing. As is shown in Figure 1, wherein the sheet-like section 14 of the plate 13 is clearly seen in side elevation, the sheet-like section 14 is shaped to provide about the periphery of the individual section or leaf a border portion 18, and extending laterally across the sheet 5 or section is a plurality of ribs or uncut portions 19 (see also Fig. 2). The laterally extending ribs 19 are connected by a plurality of parallel vertical bars or elements 20, all of these parts or portions of each sheet-like section being preferably formed integrally one with another and out of the initial sheet of lead.

As is further set forth in the above-mentioned disclosure, the bars 20 are preferably given a circular cross-section, as is clearly shown in the sectional view on an enlarged scale in Figure 3. With this construction of each of the sheet-like sections 14, 15, 16 and 17, many practical advantages are achieved; in this connection it might be pointed out more specifically that there results such a relation between the stresses exerted by the active material being formed on each bar 20 as by the Planté process, or during the action in use of the plate, to the resistance of each bar 20 to elongation, that the expansive stresses exerted upon the bar by the active material undergoing change thereon are never exceeded by the resistance 25 of the base metal of the bar 20 itself to elongation. Accordingly, each bar 20 may follow the changes which the active material undergoes, principally upon formation, and thus each sheet-like section, as the sections 14, 15, 16 and 17, for example, may similarly follow the changes to which the active material is subjected. With the arrangement and construction, as specifically shown and described herein for achieving 30 the above described action, shedding or peeling of the active material from the base metal of the active plate portions is effectively avoided; similarly uniformity of action and freedom from warping in use, in 35 so far as each individual sheet-like section is concerned, are effectively achieved.

Considering now more in detail the mechanical relation to each other of the sheet-like sections of the plate 13, it may first be pointed out that the plate 13 comprises two outer sheet-like sections or leaves 14 and 17, and a plurality of inner or intermediate leaves, shown as two in number, namely, the sections 15 and 16 (see Fig. 2). It may further be pointed out that in a plate built up of a plurality of sheet-like sections or leaves, it is found that during the action of the plate, particularly during the process of formation of the active material upon the base lead, the outer sections or leaves, such as

the sections 14 and 17, for example, of Figure 2, are more active than the inner or intermediate leaves, such as the leaves 15 or 16, and thus partake of a greater degree of change, specifically of expansion as during 70 the formation process. One of the dominant aims of this invention is to provide a construction wherein such different degrees of expansion of the individual sections or leaves may freely take place without causing 75 undesirable results, such as buckling or distortion, for example.

In carrying out this feature of this invention, I preferably form the two outer leaves or sections 14 and 17 out of a single 80 sheet of lead and of sufficient length to include therein these two leaves. This single or integral member out of which the two leaves 14 and 17 are formed is then bent or 85 folded over the bottom edges of the intermediate or inner leaves 15 and 16, as is indicated clearly in Figures 1 and 2 at 21. All of the leaves or sheet-like sections, illustratively shown as four in number, and comprising the two outer leaves 14 and 17 and the 90 two intermediate leaves 15 and 16, are then mechanically and electrically connected together along their upper edges or at the top of the plate. This connection is preferably made as by burning the sections together 95 along their upper edge, as along the edge 22 (see Fig. 1). The intermediate sections or leaves 15 and 16 have formed thereon depending lugs 15^a and 16^a, respectively (see 100 Fig. 2), shown as two in number for each of the intermediate sheet-like sections. Registering lugs of adjacent intermediate sections, such as the lugs 15^a and 16^a of Figure 2 are securely fastened together, as by burning, for example, thus forming two rigid 105 downwardly projecting lugs spaced laterally of the plate as a whole, and thus to form rigid struts or legs for supporting the plate out of contact with the bottom 11 of the container 10. Preferably, these spaced supporting 110 legs are spaced in like degree with the spacing of the upstanding ribs 12 in the bottom member 11, so that the former may rest upon the latter. These upstanding ribs 12, being of inert material, thus effectively hold 115 any conductive parts of any of the plates 13 in the container 10 out of contact with any conductive or active material which may be freed from the battery plates and be deposited upon the bottom 11 of the container 120 10. The bottom surfaces of the lugs 15^a and 16^a resting upon the ribs 12 are preferably recessed as indicated at 16^b in Figure 1, so that the ribs enter these recesses and the plates are thereby held against lateral displacement within the casing.

The two spaced lugs, such as the member 16^a of Figure 1, formed by burning together 125 registering depending lugs of adjacent intermediate sections of the plate, pass through 130

suitable openings formed in the single sheet out of which the outer sections 14 and 17 are formed. In Figure 1 these openings are shown at 22 and 23, and it will be seen that these openings are cut in the sheet out of which the two outer plate sections are formed at that portion thereof where the single sheet of lead is bent or looped around the lower edge portions of the intermediate plate sections.

Each of the individual sheet-like sections of the plates 13 is provided with an upwardly directed lug 24 (Figs. 1 and 2), lugs 24 of adjacent registering sheet-like sections being burned together with the burning together of the upper edge portions 18 of these sections. Adjacent plates 13 are separated from each other by a suitable separator 25^a, suitably porous or preferably 20 perforated, as indicated in the drawings, thus to prevent short-circuiting of adjacent plates 13 of opposite polarity while, at the same time, permitting free circulation of the electrolyte therethrough. The upstanding 25 lugs 24 of plates of like polarity are burned to an inter-connecting conducting bar 25 extending transversely of the container 10. Similarly upstanding lugs 24 of plates 13 of the other polarity are burned to an inter- 30 connecting lug or bar 26. To each of these inter-connecting lugs 25 and 26 is secured a suitable vertically and upwardly extending terminal member 27, preferably of cylindrical shape, and provided at its upper end 35 with any suitable means, such as a clamping device, for making an electrical connection to the plates of the cell.

Each of these terminal members 27 passes through a suitable stuffing box in the upper 40 or closing wall 28 of the container 10. This stuffing box may comprise an annular depending flange portion 29, through which the terminal 27 passes and forming a support for a suitable packing material 30, which may conveniently take the form, for 45 example, of a soft rubber washer. A bushing 31 surrounds the terminal 27 and is threaded into the opening in the cover plate 28 into which the packing material 30 is received, thus permitting the latter to be 50 compressed to any desired degree to hold the parts in tight sealing relation. More specifically, it will be noted that the construction of the stuffing box is such that the 55 terminal members 27 may partake of a movement relative to the cover plate 28 while maintaining the seal between the parts.

Considering now briefly the action of this plate construction and mounting, it might 60 first be pointed out that each composite plate 13 is supported upon the upstanding ribs 12 of the bottom member 11 of the container 10. Bearing in mind that the lugs (16^a of Fig. 1) are downwardly directed 65 extensions of the inner sections 15 and 16

of the composite plate 13, it may first be pointed out that the inner sections, as the members 15 and 16, may freely expand in a vertical direction in response to the changes brought about by the formation of 70 the active material upon the active elements of these inner sections. Thus, the stuffing boxes permit the terminals 27 to move therethrough vertically in response to any tendency of the upper edge portions of the 75 inner members 15 and 16 to be moved upwardly by any expanding tendencies or actions of the active material thereon. At the same time, however, it will be noted that the outer sheet-like sections 14 and 17 80 which, as above pointed out, are subjected to a greater expansive tendency by the active material, particularly during the process of formation, are free to expand in a downward direction with respect to the upper 85 edge portions 18 of the inner sections 15 and 16 to which the outer sections are rigidly secured. Thus, there is achieved such an independence of mechanical action of the outer plate sections with respect to the inner 90 sections that undesired buckling or distortion of the sections or leaves is effectively prevented. In this connection, it might also be pointed out that during the charge and discharge of the battery, expansion and contraction, respectively, of the plates tends to take place; but even during such operation of the battery, entire flexibility and independence of action, as above described, of the outer plate sections with respect to the 95 inner plate sections may readily take place, thus also safeguarding the plates against warping, buckling or distortion, even during the actual operation of the battery. More particularly is the above described 100 construction adapted for use in the positive plate of the storage cell, inasmuch as the greatest changes, due to the formation of active material upon the plate, take place in the positive plate.

It may also be noted at this point that each composite plate is of a highly advantageous compact construction; the outer plate sections 14 and 17, being in effect connected together (as at 21) at their lower 115 ends so as to envelope the lower end edges of the intermediate plate sections, thus forming substantially a mechanical casing for the intermediate plates, holding the latter in the desired mechanical relation, but additionally constitute material portions of the active sections of the composite plate. The outer sections 14 and 17, thus arranged, may thus not only contribute to the efficient electrical and mechanical action of each composite plate, but also act to insure and maintain the desired mechanical relation between the several sections or leaves of the composite plate. A distinct advantage from 120 this arrangement resides in the fact that it 125 130

becomes quite feasible, and I prefer, to use simple forms of separators between adjacent plates, such as the members 25.

While I have hereinabove specifically illustrated and described my invention in conjunction specifically with plate sections according to the disclosure in my above-mentioned co-pending application, it will be understood that many of the advantages of this invention may be achieved with other forms of individual sections, but that the advantages of my invention may be realized in practice to a peculiarly greater extent with the preferred embodiment illustrated.

It will thus be seen that there has been provided in this invention a storage cell and plate construction in which the several objects hereinbefore pointed out and many thoroughly practical advantages are achieved. It will also be seen that the construction is of such a character as to lend itself readily to inexpensive manufacture, convenience and rapidity of assembly, and that these and many other practical advantages are achieved without detracting from efficient and dependable action of the battery when in use.

As many possible embodiments may be made of the above invention and as many changes might be made in the embodiment above set forth, it is to be understood that all matter hereinbefore set forth is to be interpreted as illustrative and not in a limiting sense.

I claim as my invention:

1. In storage battery construction, in combination, a plate comprising a plurality of sheet-like sections, means for supporting one of said sections in substantially upright position within a container, said one section having a downwardly directed extension adapted to rest upon a part of the bottom of said container, and means for supporting another of said sections in depending relation with respect to said first-mentioned section, said two sections being capable of independent relative longitudinal expansion and contraction, said other section having means for slidably engaging said downwardly directed extension to guide said plates in their relative movements of expansion or contraction.

2. In storage battery construction, in combination, a plate comprising a plurality of sheet-like sections, means for supporting one of said sections in substantially upright position within a container and arranged to permit said section, upon expansion thereof, to elongate in an upward direction independently of the other sections, and means for supporting another of said sections with respect to said first-mentioned section to permit, upon expansion, elongation thereof in a downward direction independently of said first section.

3. In storage battery construction, in combination, a plate comprising a plurality of sheet-like sections adapted to rest in substantially upright position in a storage battery container, means for supporting the inner section of said plate to permit elongation, upon expansion thereof, in an upward direction, and means for supporting the outer sections of said plate to permit elongation, upon expansion thereof, in a downward direction.

4. In storage battery construction, in combination, a plate comprising a plurality of sheet-like sections adapted to rest in substantially upright position in a storage battery container, means for supporting the inner section of said plate to permit elongation, upon expansion thereof, in an upward direction, and means for supporting the outer sections of said plate in depending relation from the upper ends of said inner section of said plate.

5. In storage battery construction, in combination, a plate comprising a plurality of sheet-like sections adapted to rest in substantially upright position in a storage battery container, means for supporting the inner section of said plate to permit elongation, upon expansion thereof, in an upward direction, and means for supporting the outer sections of said plate to permit elongation, upon expansion thereof, in a downward direction, said sections having inter-engaging parts adapted to guide one section relative to the other upon relative movement therebetween taking place.

6. In storage battery construction, in combination, a plate comprising a plurality of sheet-like sections adapted to rest in substantially upright position in a storage battery container, means associated with the bottom of said container adapted to support in substantially upright position but spaced therefrom an inner section of said plate, and means for supporting the outer sections of said plate in depending relation with respect to said inner section.

7. In storage battery construction, in combination, a plate comprising a plurality of sheet-like sections adapted to rest in substantially upright position in a storage battery container, means associated with the bottom of said container adapted to support in substantially upright position but spaced therefrom an inner section of said plate, and means for supporting the outer sections of said plate in depending relation from the upper end of said inner section.

8. In storage battery construction, in combination, a plate comprising a plurality of sheet-like sections adapted to rest in substantially upright position in a storage battery container, means for supporting an inner section of said plate in substantially upright position within said container but

spaced from the bottom of said container, means for supporting the outer sections of said plate in depending relation with respect to said inner section, and means for mechanically connecting together said outer sections adjacent their lower ends, said last-mentioned means being integrally formed with said outer sections.

- 5 9. In construction for storage battery plates, in combination, a storage battery plate comprising a plurality of leaves substantially parallel and face to face fixed together at their upper ends, the two outer leaves having means connecting their lower ends and the intermediate plates having supporting parts projecting through openings in said connecting means, said intermediate leaves being fixed together adjacent said projecting parts thereof.
- 10 10. In construction for storage battery plates, in combination, a storage battery plate comprising a plurality of leaves substantially parallel and face to face fixed together at their upper ends, the two outer leaves having means connecting their lower ends, and the intermediate leaves having parts adapted to support the same in upright position and projecting through openings in said connecting means.
- 15 11. In construction for storage battery plates, in combination, a storage battery plate comprising a plurality of leaves substantially parallel and face to face fixed together at their upper ends, the two outer leaves comprising one continuous member
- 20 unconnected with the inner leaves except at said upper ends and the intermediate leaves being fixed together adjacent their lower ends.
- 25 12. In construction for storage battery

30 plates, in combination, a storage battery plate comprising a plurality of leaves substantially parallel and face to face, the two outer leaves comprising a continuous member extending about one end of the intermediate leaves, and said intermediate leaves having parts adapted to support them in upright position and extending through openings in said continuous member.

35 13. In construction for storage battery plates, in combination, a storage battery plate comprising a plurality of plate-like sections substantially parallel and face to face, the outer sections thereof being connected together at one end and the intermediate plates projecting through openings in said connecting part.

40 14. In construction for storage battery plates, in combination, a storage battery plate comprising a plurality of plate-like sections substantially parallel and face to face, means joining said sections together and adapted to permit relative longitudinal expansion thereof, and means adapted to guide said plates relative to each other in their movements of relative expansion.

45 15. In construction for storage battery plates, in combination, a storage battery plate built up of a plurality of leaves positioned substantially parallel and face to face and connected at their upper ends, the two outer leaves thereof being connected together at their lower ends and unconnected with the intermediate leaves except at said upper end connection.

50 In testimony whereof, I have signed my name to this specification this 24th day of September, 1924.

55 THEODORE S. COLE.
